UNITED STATES PATENT OFFICE.

JOHN L HANSON, OF BOSTON, MASSACHUSETTS.

IMPROVEMENT IN HEATING-STOVES.

Specification forming part of Letters Patent No. 44,089, dated September 6, 1834.

To all whom it may concern:

Be it known that I, JOHN L. HANSON, a resident of Boston, in the county of Suffolk and State of Massachusetts, have invented an Improved Stove; and I do hereby declare the same to be fully described in the following specification and represented in the accompanying drawings, of which—

Figure 1 is a front elevation, Fig. 2 a vertical and transverse section, and Fig. 3 a vertical and longitudinal section, of it. Figs. 4 and 5 are horizontal sections taken through the two flue-chambers of the base.

In the said drawings, A denotes the external case or body of the stove, which surrounds a fire-pot, E, rests on a bottom or chambered base, B, and is provided with an ash-chamber, C, which is arranged beneath the grate D of the said fire-pot. The body or case A makes about the fire-pot a smoke space or chamber, F, which at bottom opens by passages a a into a similar chamber, G, which extends wholly or partially around the ash chamber.

The fire-pot is provided with a throat, b, which is furnished with an opening, c, and a door, d, thereto, the fuel for the fire pot being supplied to it through the said opening and throat. The ash-chamber also has an opening, e, at its front, such opening e being provided with one or more doors, f f. This latter opening is for the admission of air to the fire-pot, as well as for the removal of ashes from the ash-chamber. The hollow base B, by means of a horizontal plate or partition, g, is divided into two flue-chambers, h i, within the lower, i, of which there are two vertical partitions, k k, which extend from the top to the bottom of the said flue-chamber i, and from the rear side of it to within a short distance of its front side, the whole being as shown in Figs. 2, 3, and 5. These partitions divide the flue-chamber i into three flues, l m l, which open into each other by passages n n. Two pipes, o o, extend down from the smoke-chamber G, and so as to lead the smoke therefrom into each of the flues l l. Furthermore, in the rear portion of the plate, there is a hole, p, which is partially encompassed by a vertical partition, q q' q², which extends from the plate g up to the top plate, r', of the base, and also from the two pipes o o, in manner as shown in Figs. 2 and 4. If desirable, there may be an opening, r, made through the part q' of the parti-

tion q q' q², which opening may be provided with a damper or sliding valve, s. Over the opening r there is a stand-pipe, t, which opens out of the flue-space h, and is closed at top. A direct-draft pipe, u, provided with a damper, v, leads out of the smoke-space F around the fire-pot and into the pipe t, which is to be furnished with a discharge-pipe, w, the whole being arranged as shown in the drawings. Besides the partitions q q' q² there are other partitions, q³ q³, in the upper flue-chamber of the base, these latter partitions extending a short distance forward from the pipes o o, as shown in Fig. 4. Heat-retainers or corrugated or bent pieces of metal may be arranged within the chamber h, as shown at x x and y y y, they being caused to extend from top to bottom of the same. Fig. 6 denotes a transverse and vertical section of one of the retainers x x, while Fig. 7 is a longitudinal section of one of those marked y. In the bottom of the base of the stove, and underneath the hole P, is an opening, z, which is furnished with a closing gate or slide, z', whose rod z² extends through the middle of the flue-space m and through the front of the base. Furthermore, there is arranged within the smoke-chamber F, encompassing the fire-pot, a series of curved flanges, a' a', which go from the top to the bottom of the said chamber and against opposite sides of it, as shown in Figs. 2 and 3. They serve to cause the smoke and volatile products of combustion, while passing down the chamber F, to course against its sides or surfaces, and thereby heat them to better advantage than would be the case were there no such flanges within it.

The operation of this stove may be thus described: While the damper v of the direct-draft flue is closed, the smoke and heated gases escaping from the fire-pot will circulate within the space around and above it, and from thence will pass through the pipes o o and into the flues l l. From these flues l l the smoke and gases will pass through the passages n n and into and through the flue m; thence up through the hole p and into the flue-space that is formed by the pipes o o and the partitions p p' p²; thence into the flues on the right, &c.; thence up the stand-pipe and to the chimney or discharge-flue. In their passage through the stove the smoke and hot

gases will impart heat to its case and base, and this heat will be absorbed and radiated thereby to excellent advantage. Whenever it may be desirable to lead the smoke directly into the stand-pipe without first causing it to flow through the base, the damper v should be opened. So, whenever it may be desirable to admit air into the base in order to diminish the draft through it, such may be accomplished by moving the slide z' so as to more or less increase the opening z .

I claim—

The combination and arrangement of the smoke spaces or chambers F and G about the fire-pot and the ash chamber, with the heating-pipes o o and the base-flues arranged around and below such pipes, substantially as specified.

JOHN L. HANSON.
